CRACKING HYDROCARBON OILS

Jacob Benjamin Heid, Chicago, Ill., assignor to
Universal Oil Products Company, Chicago, Ill.,
a corporation of South Dakota

Application November 26, 1930, Serial No. 498,236

1 Claim. (Cl. 196—58)

This invention relates to improvements in the art of cracking hydrocarbon oils and refers more particularly to an improved process and apparatus wherein relatively heavy hydrocarbon oils are converted into substantially lighter and more valuable products, with the resultant production of heavier liquid products, such as fuel oil and the like.

Primarily, the invention comprises introducing a regulated proportion of cooling medium upon the surface of a body of residual liquid maintained within a chamber of an oil cracking process, where, due to the relatively high temperatures maintained therein, the cooling medium is vaporized, the vapor tension of the residual liquid is increased, and a vaporization of the light components of the residual liquid is further assisted. At the same time, due to the vaporization of the cooling medium and the light components of the residual liquid, a substantial cooling of the remainder of the body of residual liquid is effected, preventing over-cracking and the formation of coke or heavy pitch-like or carbonaceous materials therein.

The principles of the present invention may be applicable to any cracking process wherein a body of heated residual products are maintained in a confined zone under any desired pressure condition, and may be especially advantageous when it is desired to effect further vaporization of the residual liquids while maintained under substantial superatmospheric pressures.

In the accompanying drawing, which is merely diagrammatic and illustrates one form of process in which the principles of the invention may be applied, raw oil charging stock may be supplied through a line 1 controlled by valve 2 to a pump 3, and may be fed through a line 4 controlled by valve 5 to fractionator 6 for pre-heating by contact with the relatively hot vapors therein and further assist in their fractionation. The preheated raw oil, together with the heavier condensed portions of the vapors from fractionator 6 may thence pass through a line 7, trap 42, and line 8, the latter being controlled by a valve 41, to a pump 9. Any desired portion or all of the raw oil may be diverted from fractionator 6 through a line 10 controlled by a valve 11, to line 8 where it may combine with reflux condensate issuing from fractionator 6, from whence it may pass to pump 9. Combined raw oil and reflux condensate may be supplied to heating element 14 through pump 9 and line 12 controlled by valve 13.

Heating element 14 may be located in any suit-

able form of furnace 15, and the oil passing therethrough may be heated to any desired conversion temperature and pressure, and may pass through line 16 controlled by valve 17 into a reaction chamber 18. Heating element 14 and reaction chamber 18 may be maintained under substantial superatmospheric pressure, or, if desired, reaction chamber 18 may be maintained under a substantially reduced pressure. Preferably, however, chamber 18 may be maintained under a substantial superatmospheric pressure to effect continued conversion of the products being passed therethrough. In ordinary cracking operations, if the unvaporized residual liquid which may separate from the vaporized conversion products in the reaction chamber is allowed to accumulate in this zone under the temperatures and pressures ordinarily prevailing therein, cracking will continue in the residual liquid as well as in the vapors, and, in fact, may be more pronounced in the liquid, resulting in the excessive formation of coke or heavy, pitch-like or carbonaceous materials, as well as increasing the viscosity of said residual liquid, rendering it undesirable for use or sale as commercial fuel.

In order to control the cracking reaction, prevent excessive cracking, and, at the same time, effect a substantial vaporization of the relatively light components of the residual liquid within chamber 18, I may introduce into said chamber 30 regulated quantities of a cooling medium, such as water in a relatively cold state, or relatively cold water and oil through a line 19 controlled by a valve 20. The cooling medium is preferably introduced in such manner as to cause it to contact directly with the surface of the hot residual liquid while said cooling medium is in its liquid state, bringing about its vaporization at substantially the point of contact on the surface of said residual liquid. In order to accomplish a liquid-upon-liquid contact, I may provide a line 21 extending throughout chamber 18 from its upper limits to substantially the predetermined liquid level of the residual products within said chamber, as exemplified by a line L—L in the drawing. If a variable liquid level be employed within said chamber, provision may be made for varying the length of the line 21 to such varying level, or, if desired, a plurality of inlet lines 19' controlled by suitable valves 20' and provided with extensions 21' 50 may be disposed within said chamber at various levels, and the cooling medium may be introduced through any of said inlets, dependent upon the level maintained in said chamber at any particular operation. Preferably, the cooling medium is 55

not introduced at a point substantially below the surface of the liquid within chamber 18, since I have found that the best results are obtained by a contact of the cooling medium with the surface 5 of the residual liquid.

To obviate the possibility of the cooling medium accumulating in the liquid state in the reaction zone, residual products may be continuously withdrawn from the lower limits of the chamber 10 18 through a line 22 controlled by a valve 23.

Vapors from chamber 18 may pass through line 15 24 and valve control 25 to fractionator 6 where their relatively heavy insufficiently converted portions may be condensed and returned to the heating 20 element 14 for reconversion, as already described, while the lighter portions of the fractionated vapors may pass through a line 26 controlled by valve 27 and be subjected to condensation and cooling in condenser 28, the resultant 25 products therefrom passing through a line 29 controlled by valve 30 to a receiver 31. Distillate may be withdrawn from receiver 31 through a line 32 controlled by valve 33. Incondensable gases may be released from receiver 31 through a line 34 controlled by valve 35. Any desired amount of the 30 distillate from receiver 31 may be withdrawn through line 36 controlled by valve 37 for recirculation by means of pump 38, line 39 controlled by valve 40 to fractionator 6 where they may assist 35 in the fractionation of the vapors within said fractionator.

To prevent any of the water which may be used 35 as the cooling medium introduced into chamber 18, and which may pass into the fractionator 6 as steam, entering the heating element 14 with the reflux products from said fractionator, a trap 42 surrounding line 7, may be attached to the fractionator 6. Products passing into said trap 42 may be withdrawn therefrom through a line 43 controlled by valve 44.

Conversion temperatures employed may range 45 from 750° to 1200° F., more or less, and the various zones of the cracking system may be operated under substantially equalized or differential pressures, ranging from sub-atmospheric to super-atmospheric of about 2000 pounds or more per square inch.

As a specific example of one operation embodying 50 my invention, a 32° A. P. I. gravity topped crude was subjected to a conversion temperature of approximately 900° F., with a substantially equalized pressure of about 200 pounds per square inch being maintained in the system. In this operation, no cooling was effected over the residual products within the reaction chamber, and a yield, based on the charge, of about 54% of motor fuel

5 was obtained, having an anti-knock value of about 35% benzol equivalent. In addition, about 12% of pressure distillate bottoms and about 26% heavy residual oil, relatively high in suspended carbon and B. S. content, unsuitable without re-treatment for sale as commercial fuel oil was produced, together with a remaining 8% of gas and coke loss.

10 In another operation, employing the same apparatus and substantially the same temperatures and pressures, but one in which a cooling medium comprising cold water in amounts equivalent to from one to five per cent of the residual products produced, was fed at a substantially constant rate upon the surface of the residual liquid maintained at a relatively low level 15 in the reaction chamber. The yields obtained were substantially the same as those in the first-mentioned operation, but the yield of residual oil was increased substantially, with a resultant 20 substantial decrease in the formation of coke, gas and pressure distillate bottoms. The residual products recovered in this latter operation were substantially free from suspended coke and B. S., meeting all requirements as to quality for commercial fuel oil, and was an excellent charging stock for relatively low temperature or liquid-vapor-phase cracking operations. As stated, the production of coke was substantially decreased, affording a prolonged operation of the process, 30 and, in addition, the motor fuel produced was relatively sweeter and more stable, with an increase in anti-knock value of about 5% or more benzol equivalent.

35 I claim as my invention:—

In a hydrocarbon oil cracking process of the character wherein the oil is heated to cracking temperature under pressure while flowing in a restricted stream through a heating zone and thence discharged into the upper portion of an 40 enlarged reaction zone maintained under cracking conditions of temperature and pressure and wherein the heated oil is separated into vapors and unvaporized oil, the improvement which 45 comprises continuously supplying water in liquid state directly to the surface of the unvaporized oil in the lower portion of the reaction zone, removing admixed oil vapors and steam from the reaction zone and dephlegmating the same to condense insufficiently cracked fractions of the 50 vapors as reflux condensate, separating entrained water from the reflux condensate, and then returning the reflux condensate to the heating zone for re-treatment therein.

55 JACOB BENJAMIN HEID.
